UNITED STATES PATENT OFFICE.

HARRIET B. HEDDEN, OF EAST ORANGE, NEW JERSEY.

STEAMER RUG OR ROBE.

Application filed October 22, 1927. Serial No. 227,922.

This invention relates to improved steamer rugs or robes.

Pursuant to my invention, a so-called steamer rug or robe of regulation or other suitable type is provided with suitable means for attachment to the body of the wearer to enable the rug to be worn in the nature of an outer garment in protection against the weather.

10 My invention is of general use, but finds particular application for use in sitting posture of the wearer as in attendance at a stadium witnessing a football game, or when riding in an automobile, or when reclining on a steamer chair and the like.

15 The more preferred forms of my invention comprise suitable means in the nature of an attachment to the regulation or other suitable steamer rug, and preferably disconnectibly attached to the steamer rug or robe proper, whereby the steamer rug is readily secured to the body of the wearer.

20 Further features and objects of the invention will be more fully understood from the following detail description and the accompanying drawings, in which

Fig. 1 is a perspective elevational view showing a preferred form of my invention;

Fig. 2 is a sectional elevation on line 2—2, 30 Fig. 1;

Fig. 3 is a perspective view illustrating one manner of use of my invention; and

Fig. 4 is a sectional elevation on line 4—4, 35 Fig. 1.

Referring to the drawings, the blanket proper 10 is of regulation type, or of any other suitable form. Usually, the blanket proper 10 is of rectangular outline, having a somewhat greater length than the width, and may have or may not have the fringe 11, 12 at its two opposite ends of length.

40 The opposite lateral sides of the rug or robe proper are designated 13^a, 13^b which may or may not be ornamented by a fringe or other finishing.

45 Any suitable form of attachment of my invention to such rug may be employed. In the form of the attachment illustrated in the drawings, the same is of suitable material such as chamois, woven fabric including cloth and the like, and preferably windproof, rainproof and possessing a relatively high coefficient of heat insulation. I have discovered that chamois serves excellently for the pur-

poses of my invention, in that it is proof 55 against wind, rain and moisture and affords a high degree of "warmth".

Such attachment comprises principally an envelope portion 14 which is formed of chamois or the like and extends from one side 50 designated generally by the line 15—15, shown in Fig. 1, of the line of attachment of the same to the blanket proximate one lateral side 13^a, to the opposite side of attachment 60 designated generally by the line 16—16 adjacent the opposite lateral side 13^b. The attachment at the side 14^a on the line 15—15 is preferably by removable means such as snap fasteners 17, one element of each snap fastener 17 being sewed, "riveted" or otherwise secured 65 to the material of the rug or robe 10 at proper spacing from one another corresponding to the spacing of the co-acting elements of such snap fasteners 17 attached to the envelope 14. Similarly, the opposite end 14^b is attached by 70 the set of snap fasteners 18.

If desired, and as illustrated in the drawings, the material of the envelope portion 14 is continued as indicated at 19 from the line of attachment 15—15 to the line of attachment 80 16—16, in which form of my invention the material of the envelope 14 forms a complete circumference independently of the portion 10^a, see Fig. 2, of the material of the rug or robe 10 disposed between the line of attachment 15—15 and the line of attachment 16—16. In such form of my invention, the material of the envelope 14 is wholly or partially slitted for its length and disconnectibly connected by means of the line of snap fasteners 20.

85 My attachment in its most preferred forms further comprises an upper portion 21, usually of the same material as the material of the envelope 14 and integral therewith. At 90 the upper margin 22 of such portion 21, I provide a belt or pair of belts 23 and suitable means for "threading" the belt to the marginal portion 22, as in the form of a series of spaced loops 24. When a single belt, as illustrated, is employed, the set of loops 25 are secured to the inner face of the rug 10. The buckle end of the strap 23 is indicated at 23^a and the free end at 23^b. As is indicated in the drawings, and as hereinafter described, the 105 belt or belts 23 are disposed to encompass the waist of the wearer.

100 As is illustrated in Fig. 4, the envelope por-

tion 14 is preferably shaped by suitable designing to provide a bulged or seat portion 14^c, which may be padded if desired.

My invention is "worn" by the wearer 5 "stepping into" the envelope portion 14, as will be understood, or the snap fasteners 20 may be unsnapped, and the envelope 14 encircled about the legs of the wearer and the snap fasteners 20 snapped to closed position.

10 While the rug 10 is held in position with one hand, the free end 23^b of the belt 23 is slipped through its buckle 23^a and the belt 23 is pulled to properly adjust the combined envelope and the rug about the waist of the wearer.

15 In Fig. 3, I have illustrated the use of my invention when worn in attendance at an outdoor sport, as at a game of football usually played in a stadium where the seats 26 are of concrete. However, such view is for 20 illustrative purposes only and it will be apparent that the advantages of my invention are similarly derived when used in seated or reclining posture outdoors generally or elsewhere in protection against the weather.

25 It will be observed that when the belt 23 has been properly adjusted to the body of the wearer, the uppermost portion 10^c, see Figs. 1 and 3, drops upon being released from the hand and when the wearer assumes a 30 seated or other reclining position, such portion 10^c forms a double fold in or at the lap of the wearer, thus enabling the fringe 12 or other ornamentation to be visible. As appears from Fig. 3, the envelope 14 of itself 35 serves to protect the lower portion of the body of the wearer and independently of the lower portion of the rug 10 in the protection of the wearer from wind, rain or other moisture and the like.

40 The use of my invention, as illustrated in Fig. 3, also makes apparent the advantage of material which is proof against "cold" which is effective when the wearer sits on a concrete seat, or on a slotted or perforated 45 seat of other material open to the atmosphere.

It will also be observed that upon the wearer rising to standing position, the rug or robe is self-supported from the waist of the wearer and enables the wearer to return 50 to seated position without disarranging the rug or the envelope.

As indicated above, my invention possesses similar advantages when worn while motorizing, or when seated or reclining on chairs on 55 steamér decks or under other similar conditions.

It will be noted that one or two standard 60 sizes of the envelope portion is adaptable for universal use, since the envelope folds readily about the body of a relatively thin person while accommodating full length for stouter persons. The height of the envelope 65 is self-adaptable for all heights of persons and is of sufficient length to be tucked under the feet.

An important feature of my invention for use at outdoor sports is that it is open at the bottom thereby enabling the wearer to walk or otherwise move about in comfort and without danger of tripping, as compared with an envelope which is of bag-form and not open at the bottom.

In lieu of snap fasteners, strips of hookless fasteners or "rip locks" may be employed, as will be understood.

Pursuant to one form of my invention, the envelope and belt or equivalent serve as an attachment to be applied to a steamer rug or equivalent previously purchased by the 80 wearer.

When it is desired to derive the benefit of protection of the upper portion 10^c of the rug or robe, the same may be held upwardly in front of the chest or "thrown" about the shoulders of the wearer.

When my invention is desired for use when basking in the sun or on steamer decks, the lower portion of my envelope may be substantially closed, by employing an extended length of the material either integral with the body portion 14 or detachably connected thereto, thus enabling the extended portion to be tucked about the feet of the wearer, or to form a substantial closure by means of snap-fasteners, hookless fastener or the like.

In lieu of a single belt as illustrated, a pair or multiple belt may be employed, by securing at the location of the loops 25 permanently or detachably the body parts of a strap having a buckle at each end and a second strap without buckles passing through the loops 24, and enabling the adjustment of the straps to be had at both sides of the wearer.

Whereas I have described my invention 105 by reference to specific forms thereof, it will be understood that many changes and modifications may be made without departing from the spirit of the invention.

I claim:

1. The combination of a robe, an open bottomed envelope arranged to envelope the nether portion of the body of the wearer and extending about the back of the wearer downwardly from the waist, and disconnectible means for connecting said envelope to said robe and said envelope and for securing said envelope and said robe to and about the waist of the wearer.

2. The combination of a robe, an open bottomed envelope arranged to envelope the nether portion of the body of the wearer and extending about the back of the wearer downwardly from the waist, disconnectible means for securing said envelope to said robe and disconnectible means for connecting said envelope at its upper margin to the robe and for securing said envelope and said robe to and about the waist of the wearer.

3. The combination of a robe, an open bot-

5 tomed envelope arranged to envelope the upper margin of said envelope to said robe
nether portion of the body of the wearer and
extending about the back of the wearer
downwardly from the waist, vertically ex-
tending disconnectible means for securing
said envelope to said robe and strap means
for connecting said envelope at its upper
margin to the robe and for securing said en-
velope and said robe to and about the waist
10 of the wearer.

4. The combination of a robe, an open bot-
tomed envelope arranged to envelope the upper margin of said envelope to said robe
nether portion of the body of the wearer and
extending about the back of the wearer
15 downwardly from the waist, the material of
said envelope substantially extending com-
pletely about the body of the wearer, discon-
nectible means disposed at one side of the
wearer for connecting the ends of the mate-
20 rial of said envelope to one another, means
for connecting said envelope to said robe,
and disconnectible means for connecting the

25 and for securing said envelope and said robe
to and about the waist of the wearer.

5. The combination of a robe, an envelope
arranged to envelope the nether portion of
the body of the wearer and extending about
the back of the wearer downwardly from the
waist, the material of said envelope substan-
30 tially extending completely about the body
of the wearer, disconnectible means located
at one side of the wearer for connecting the
ends of the material of said envelope to one
another, disconnectible means for connecting
35 said envelope to said robe, and strap means
for connecting the upper margin of said en-
velope to said robe and for securing said en-
velope and said robe to and about the waist
of the wearer.

40 In testimony whereof I have signed this
specification this 19th day of October, 1927.

HARRIET B. HEDDEN.
